UNITED STATES PATENT OFFICE.

AXEL TOLF, OF CHICAGO, ILLINOIS.

COUNTERBALANCING ELEVATOR-DOOR.

No. 927,012.

Specification of Letters Patent.

Patented July 6, 1909.

Application filed May 13, 1908. Serial No. 432,658.

To all whom it may concern:

Be it known that I, AXEL TOLF, a citizen of the United States, and resident of Chicago, county of Cook, and State of Illinois, have 5 invented certain new and useful Improvements in Counterbalancing Elevator-Doors, of which the following is a specification and which are illustrated in the accompanying drawings, forming a part thereof.

10 The invention relates to doors for elevator shafts, of the type comprising a pair of oppositely-moving counterbalancing and vertically-sliding doors. The common practice has heretofore been to connect such doors by 15 means of chains or cables running over sheaves. This arrangement involves considerable friction, and consequently the doors are operated with difficulty.

This invention has for its object the simplification of structures of this character, cheapening their cost of manufacture and rendering them more easy and certain of operation, and it consists in the structure hereinafter described and which is illustrated in 25 the accompanying drawings, in which,—

Figure 1 is a front elevation of the doors as applied to an elevator shaft; Fig. 2 is a detail elevation of one of the doors, some parts being broken away; Fig. 3 is a detail elevation 30 of the lever mechanism for connecting the doors; Fig. 4 is a sectional detail on the line 4—4 of Fig. 1; and Fig. 5 is a sectional detail on the line 5—5 of Fig. 3. Fig. 6 is a front elevation of the doors as applied to an elevator shaft, showing a modified form of construction, Fig. 7 is a sectional view on the line 35 7—7 of Fig. 6.

A pair of uprights, forming the door frame of an elevator shaft, is shown at 10, and to 40 these uprights are secured Z-plates 11 and 12 constituting the runways for the doors 13, 14. Each of these doors as shown comprises a frame 15 of angle bars and a sheet-metal panel 16 secured to the frame.

45 The two doors are provided with operating levers, pivoted to the frame members 10, and linked together in such a manner that they move in opposition, and consequently simultaneously open and close both doors. For

50 the purpose of insuring free movement of the doors, the levers are duplicated, there being a set at each side of the doorway, but an operating handle need be applied to one side only. As the two sets of levers for opposite 55 sides of the door are alike, but one of them need be described. The doors are arranged

in vertical alinement. A lever 17 pivoted at 18 to the door frame 10, or, as shown, to a plate 19 secured thereto, has its inner end connected by means of a link 20 to the upper 60 corner of the upper door 13; and a similar lever 21, pivoted at 22 to the plate 19, has its inner end connected by means of a link 23 to the lower corner of the lower door 14. These 65 levers are L-shaped, their angles 24, 25 projecting toward each other and being adjacent their fixed pivots 18, 22, this form of lever providing a longer range of movement without carrying its free end beyond the side of the door. One 70 of the levers—as shown, the one coöperating with the upper door—has an extension 26 projecting beyond its fixed pivot, and a link 27 connects this projection with the lower lever 21, being attached thereto at its elbow 75 25. The levers are actuated by means of a bar 28 attached to one of them, as shown, to the elbow 24 of the lever 17, and being provided with a handle or grip member 29, which may be grasped by the operator. A 80 spring latch 30 is pivoted to the grip member 29 and projects through an aperture in the bar 28 and engages the inner angle of the elbow 25 of the lever 21 when the doors are closed, and as it thus lies in the path of the lever, it effectually locks the doors, thereby 85 rendering it impossible to open them from the outside. A guide rod 31, 32 is attached to the side and outer end member of the frame of each of the doors, lying over the 90 links 20 and 23, thereby preventing swaying of the levers while permitting their free movement, the ends of the guide rods being attached to the side of the door at a distance from its outer corner less than the length of the link with which it coöperates.

95 The doors are opened by grasping the grip member 29 and latch 30 and swinging the bar 28 inwardly, or toward the doors thus throwing the lever 17 upwardly and the lever 21 downwardly. The doors may be exactly 100 equal in weight, and hence the only resistance to their movement is found in the friction. As the pivots of the various levers and links produce no material friction, practically the only load to be overcome is the friction 105 of the doors in their ways.

For the purpose of affording more firm anchorage for the pivots of the levers, their inner ends may be covered by a plate 33 bolted to the plate 19.

110 When, as is sometimes necessary, the doors are made of more than two sections,

the form of construction illustrated in Figs. 6 and 7 may be employed. As there shown the door as a whole comprises the sections 34, 35, and 36, 37, the two former being movable 5 downward and the two latter movable upward. There are provided the double ways 38, 39, the sections 34, 36, sliding in the one, and the sections 35, 37, in the other. The door sections 34, 36, are supported by means 10 of the levers 17 and 21, as in the construction illustrated on Figs. 1 to 5, connection between these levers and the door sections being by means of the links 20 and 23, attached to the ends of the levers. The door 15 sections 35, 37, are supported by means of links 40, 41, respectively, attached to the levers intermediate of their ends, thereby giving these door sections a less range of movement than the sections 34, 36, so that when 20 the door is opened the inner sections slide alongside the outer sections. In this construction the same counterbalancing action is secured with consequent ease of operation. The lever movement herein shown and de- 25 scribed has, in addition to the advantages hereinbefore pointed out, the further advantage of avoiding violent action in closing. The initial movement in opening is comparatively slow because of the position of the levers, and in closing the final movement is correspondingly retarded, the doors making a gentle contact and thus avoiding strain upon the parts. Furthermore, the various 30 pivots employed for the levers and links may be made much stronger than it is possible to utilize where chains are relied upon, without making the latter unduly cumbersome. While I have shown in Figs. 6 and 7 four 35 door sections, it is obvious that the number 10 may be varied, the invention being equally applicable to a situation in which any number of sections are employed. It not infrequently occurs that it is found desirable to make doors of this class in three sections, two 45 of them moving in one direction and one in the other, and it will be seen that, referring to Fig. 6, either the lower section 35 or the upper section 37 may be dispensed with, it becoming necessary only to make the re- 50 maining single section sufficiently heavy to

counterbalance the two sections moving in the opposite direction, and this will usually result from the larger size of the single section.

I claim as my invention,—

1. In combination, a pair of oppositely-opening sliding doors, ways for the doors, a pair of levers pivoted to the ways and each connected to one of the doors, a link connecting the levers and being attached thereto at 60 opposite sides of their pivots, a handle bar attached to one of the levers, and a spring latch attached to the handle bar and engaging one of the levers.

2. In combination, a pair of oppositely moving sliding doors, one thereof being composed of two sections, ways for the doors, a lever pivoted to one of the ways, a link connecting the lever to one of the doors, a second lever pivoted to one of the ways, links connecting such lever to the two sections of the other door and being attached to the lever at differing distances from its pivot.

3. In combination, a sliding door comprising a plurality of sections arranged in oppositely-moving sets, ways for the several sections, levers pivoted to the ways, and links connecting each lever to a plurality of sections and being attached to the levers at differing distances from their pivots.

4. In combination, a sliding door comprising a plurality of sections, ways for the sections, levers pivoted to the ways, and links connecting each lever to a plurality of sections and being attached to the levers at different distances from their pivots.

5. In combination, a sliding door comprising two oppositely-moving groups of sections, ways for the sections, levers pivoted to the ways, a link connecting the levers and attached thereto, respectively, at opposite sides of their pivots, and links connecting each lever with the several sections of one of the groups, such links being attached to the levers at different distances from their pivots.

AXEL TOLF.
